UNITED STATES PATENT OFFICE.

JOHAN A. ANDERSON, OF CRANSTON, RHODE ISLAND, ASSIGNOR TO UNIVERSAL WINDING COMPANY, OF BOSTON, MASSACHUSETTS, A CORPORATION OF MASSACHUSETTS.

COP HOLDER FOR TEXTILE MACHINES.

Application filed October 17, 1925. Serial No. 63,005.

This invention relates to cop-holders for use on creels, winding machines or other textile apparatus, and particularly to a cop-holder for supporting cones of yarn, thread and the like.

A principal object of the invention is to provide a device of the type specified for gripping the interior of the tube on which the cone, cop or other package is wound to secure it rotatively with and longitudinally of the spindle which serves as its support.

Another object of the invention is to provide a device of the type specified which will act automatically to grip the tube when the latter is pushed onto the spindle without requiring the operation of levers, dogs, or other mechanical gripping- or expansion-means.

Another object of the invention is to provide a device of the type specified which will hold the cop-tube firmly and securely in place on the spindle without danger of its accidental release, but which will release the tube to allow its manual removal when a strong pull is exerted thereon.

Another object of the invention is to provide a device of the type specified which is proof against derangement or getting out of order and durable in use over long periods without excessive wear or deterioration.

Another object of the invention is to provide a device of the type specified which is simple and convenient to construct and economical in its cost of manufacture.

Further objects of the improvement are set forth in the following specification which describes a preferred embodiment of the invention as illustrated in the accompanying drawings. In the drawings:

Fig. 1 is a view showing my improved cop- or cone-holder as applied to use, and illustrating the gripping-means thereof in section taken in an axial plane;

Fig. 2 is a perspective view of the sleeve employed for attaching the gripping-means to the spindle; and

Fig. 3 is a perspective view of the resilient gripping-means.

Referring to Fig. 1 of the drawings, 2 designates a rod or shaft which may constitute the rotating spindle of a winding machine or other textile apparatus, or the fixed spindle or skewer of a creel or supply-stand. In the latter case the rod or spindle

2 may be held in a hub or boss 3, forming a

part of or attached to the creel frame, and fastened in place by a set-screw 4.

On the outer end of the spindle 2 I preferably place a hub or collar 5 fastened thereto by a set-screw 6 and having its forward rim beveled off at 7. Positioned rearwardly from the collar 5 is a sleeve or bushing 10 secured to the spindle 2 by suitable means, such as the set-screw 11. The sleeve 10 is provided with an annulus or flange 12 65 against the face of which is held the resilient gripping-element 15 for securing the cop-tube C in position on the spindle 2.

In accordance with the present improvement the gripping-means for the cop-tube 70 takes the form of a concavo-convex disk or washer 15 which may be constructed of rubber or other suitable resilient material. The disk 15 has an axial hole 16 adapting it to slip over the threaded portion 17 of the 75 sleeve 10 to seat it against the flange 11. A washer 18 is then placed against the forward side of the rubber disk 15 and a nut 19 screwed onto the sleeve 10 to bind the disk between the flange 11 and washer 18. 80

Normally, the rubber disk or washer 15 is only slightly concaved on its rearward side as illustrated by the dash lines in Fig. 1, but when the cop-tube C is slid on to the spindle 2 it will flex the disk 15 to convex it to a greater degree, as illustrated by the full lines in Fig. 1, whereby its rim will be caused to bind tightly against the interior of the cop-tube to frictionally grip the latter. As the tube C is pushed onto the spindle 2 its outer end will bear on the hub or collar 5 to centralize the tube with respect to the axis of the spindle, and the inner or larger end of the tube will likewise be held concentric with the spindle by the resilient 95 disk 15.

The tube C is usually made of paper pulp, fiber or similar material and its inner surface is somewhat rough. Therefore, the edge of the resilient disk 15 will grip the 100 interior of the tube very firmly and securely and prevent its withdrawal from the spindle 2 under ordinary conditions. That is to say, the tube C will be held by the frictional grip of the disk 15 to secure it rotatively with 105 and longitudinally of the spindle 2 as the latter is operated to wind yarn or thread on the tube in the form of a cone or package as indicated by dash lines in Fig. 1. When the cone or cop 110 completed a strong pull

on the tube will cause the resilient disk 15 to yield radially and to flex in the opposite direction to release the tube so that it may be removed from the spindle and a new tube applied thereto.

Where the spindle 2 is employed as a support or skewer for holding cones or other packages on a creel or supply-rack the resilient disk 15 acts in the same manner to grip the interior of the tube C to prevent it from pulling off or becoming disengaged as the yarn is unwound from its surface, but allowing its removal under a sharp pull when the yarn has been completely unwound.

It will be observed that my invention provides an especially simple and inexpensive device for securing cop-tubes on spindles or skewers and one which is automatic in operation without the use of complicated mechanism. That is to say, there are no springs, levers, dogs or other expansible gripping-elements, the resilient disk or washer 15 acting as the single gripping- or securing-means and being proof against wear, derangement or getting out of order. Furthermore, in operation the device grips and secures the cop-tube to the spindle by the simple action of placing it thereon and when once gripped it is practically proof against accidental removal. At the same time, the tubes may be released and removed from the spindle by simply exerting a pull thereon without entailing the manipulation of levers or other mechanism and without requiring any special skill or expertness on the part of the operator.

While I have herein shown my improvement as embodied in a preferred form of device, various modifications may be made in the structure and arrangement of its parts without departing from the spirit or scope of the invention. Therefore, without limiting myself to the exact details of design and construction as herein illustrated and described, I claim:

1. A cop-holder for textile apparatus comprising means on which the cop-tube is supported and a resilient concavo-convex disk adapted to grip the interior of the tube to secure it to the supporting-means while holding it concentrically thereof and to flex to permit its removal therefrom.

2. In a cop-holder for textile machines, the combination of a spindle, and a resilient

disk of concavo-convex cross-section projecting radially from the spindle to adapt its rim to frictionally grip the interior of the cop-tube to hold it in place concentrically of the spindle and to flex to release the tube when a pull is exerted thereon.

3. In a cop-holder for textile machines, the combination of a spindle, a threaded sleeve on the spindle provided with an annular flange, a resilient disk seated against the face of the flange, and a nut screwed onto the sleeve to clamp the disk against the flange.

4. A cop-holder for textile machines comprising a spindle having means for rigidly supporting one end of the cop-tube and a disk of resilient material arranged with its peripheral rim engaging the opposite end of the cop-tube to maintain the latter in concentric relation with the spindle, said disk susceptible of flexure to cause it to grip the interior of the tube to secure the latter longitudinally of the spindle while adapting it to release the tube under a pull thereon to provide for its removal from the spindle.

5. In a cop-holder for textile machines, the combination of a spindle having means for engaging the interior of a conical cop-tube adjacent the apex end thereof, and a resilient disk projecting radially from the spindle to adapt its rim to engage the interior of the larger end of the cop-tube to support the latter in concentric relation with the spindle, said disk also adapted to frictionally grip the walls of the tube to secure it longitudinally of the spindle and being capable of flexure to permit the release of the tube from the spindle.

6. In a cop-holder for textile machines, the combination of a spindle, means at the end of the spindle for engaging the interior of the cop-tube to support one of its ends in concentric relation with the spindle, and a resilient disk projecting radially from the spindle with its peripheral rim adapted to engage the interior of the cop-tube adjacent its other end, said disk adapted to flex to conform to the interior of the cop-tube whereby to support the latter in concentric relation with respect to the spindle and to frictionally grip the interior of the tube to secure it in place on the spindle.

In testimony whereof I hereunto affix my signature.

JOHAN A. ANDERSON.
